COMPRESSED-AIR STARTING ARRANGEMENT FOR INTERNAL-COMBUSTION ENGINES.

1,413,583.

Specification of Letters Patent. Patented Apr. 25, 1922.

Application filed December 3, 1920. Serial No. 428,125.

To all whom it may concern:

Be it known that I, ERNST HERKT, residing at Kiel-Hassee, Germany, Hamburger, Chaussee 101, a citizen of the German Republic, have invented certain new and useful Improvements in Compressed-Air Starting Arrangements for Internal-Combustion Engines, of which the following is a specification.

10 The object of this invention is a compressed air starting arrangement for internal combustion engines and the like, the control apparatus of which, moving the compressed air starting valve, is automatically 15 thrown into and out of gear on admitting and cutting off the compressed air.

From known arrangements of this kind, with which, on turning on the compressed air, a prolongation of the connecting rods 20 takes place, throwing them into gear, and with which the compressed air cylinder causing the prolongation of the connecting rods forms so to say an elastic connection link inserted between two parts of the connecting means, the object of this invention 25 differs in so far that, on turning on the starting compressed air, neither a change in the position nor a change in the length of the connecting rods takes place, this being 30 prevented by the cam disk of the control device. Only at a determined position of the cam disk (starting position) this blocking is released and thus the pressure means has the possibility to increase its volume and 35 thus to cause the opening of the starting valve. As, according to the invention, the length of the connecting rods remains permanently constant, the disadvantages of the first named known control device combined 40 with the prolongation of the connecting rods and the insertion of an elastic member into the chain of rods, are avoided and a more precise working of the control device is obtained. Besides, the control device is ex- 45 ceedingly simplified by the almost total absence of connecting rods.

On the drawing one embodiment of the object of the invention is shown in section.

A is the part in question of the cylinder 50 head of an internal combustion engine provided with the valve box B of the compressed air starting valve, and the compressed air feeding conduit α^1 . In the upper part of the boring of the box B a piston C capable of a movement up and down

is arranged concentrically around the valve rod D. When at rest, the piston C bears with its lower surface against the bifurcated end of the arm h^1 of the valve lever H. The starting valve d^1 opening towards the interior of the working cylinder is in its rest position held closed by the spring E provided in the lower part of the valve box. This spring presses from below against a collar d^2 of the valve rod and presses this 65 collar against the lower surface of the bifurcated end of the valve lever arm h^1 .

The valve rod has a boring d^3 , through which the starting compressed air can enter the room above the piston C. The valve lever H oscillating around the valve lever shaft G carries on its right arm the starting roll h^2 working together with the cam disk K h^1 , whilst its left arm h^1 embraces with play the valve rod D between the piston C 75 and the collar d^2 .

The described starting arrangement works as follows:

When at rest or in normal working condition, the different members of the starting apparatus occupy the position shown in the drawing. The piston C presses by its weight on the arm h^1 of the valve lever and on the collar d^2 of the rod D. Against this pressure the valve plate d^1 is pressed upward 80 by the spring E on its seat, consequently the valve held closed. The pressing of the starting roll h^2 against the cam disk K by the pressure of the piston C on the arm h^1 of the valve lever is partly neutralized by a 85 spring N. When for the purpose of starting or reversing compressed air is admitted into the conduit α^1 , the piston C tends to move downwards and thus the starting roll h^2 is pressed firmer against its running surface 90 on the cam disk K. A real downward movement of the piston C can, however, not take place, as the valve lever H is prevented by the roll h^2 from turning around the valve lever shaft G. Only after the cam disk 95 K has turned so far under the action of the other cylinders of the engine that its cavity h^1 (negative cam face) passes under the roll h^2 , the piston C can move downwards, press down the valve rod by means of the collar 100 d^2 and open the starting valve d^1 , so that the compressed air can flow into the cylinder. On the going down of the valve rod the spring E is compressed; as soon as the cavity h^1 of the cam disk K has passed under 105

the roll h^2 . The valve is closed again by the spring E, and the piston C pressed back into its initial position by the arm h^1 of the valve lever H. This working order repeats itself as long as the feeding of the compressed air lasts, that is till the engine is reversed to combustion running. As soon as the pressure in the working cylinder surpasses the pressure of the starting compressed air the starting valve is automatically closed in consequence of the difference in pressure.

Claims.

1. A compressed air starting device for internal combustion engines comprising a port formed in the head of the engine for the admittance of compressed air, a valve for closing said port, a valve stem, a piston on said valve stem, a chamber in which said piston works, a valve lever operatively engaging said valve stem, a cam disc for controlling said valve lever and means acting upon said piston for opening said valve upon rotation of said cam disc.
2. A compressed air starting arrangement for internal combustion engines provided with a control apparatus, said control apparatus comprising a valve for controlling the admittance of compressed air, a valve rod provided with a piston, a chamber in which said piston operates, means for admitting air to one side of said piston, thereby tending to open said valve, a valve lever in engagement with said valve stem and a cam disc for controlling said valve lever, whereby said lever may be released to permit the pressure on said piston to open said valve.
3. A starting arrangement for internal

combustion engines comprising a control device for controlling the admittance of compressed air thereto, said control device embodying a valve, compressed air means normally tending to open said valve, a double-armed valve lever engaging said means and retaining said valve in its closed position, a cam disc engaging one end of said valve lever, whereby when said cam disc is rotated to a pre-determined position said valve lever will be released to permit said valve to open.

4. A compressed air starting device for internal combustion engines comprising a valve for controlling the admittance of air to the engine cylinder, a valve stem for said valve, a piston secured to said valve stem, a chamber in which said piston works, means for supplying air to the upper side of said piston, whereby pressure may be accumulated tending to open said valve, a valve lever pivotally supported adjacent said valve stem, said valve lever having a bifurcated end which engages said valve stem beneath said piston, a spring surrounding said valve stem tending to seat said valve, a cam disc, the other end of said valve lever engaging said cam disc, said valve lever tending to prevent the opening of said valve, said valve lever permitting the opening of said valve when said cam disc has rotated to a pre-determined position.

The foregoing specification signed at Kiel, Germany, this 29th day of June, 1920.
